UNITED STATES PATENT OFFICE

DE WITT C. HAWORTH, OF BANDON, OREGON, ASSIGNOR OF ONE-FOURTH TO CHARLES DAVIS, ONE-FOURTH TO O. L. ZENTNER, OF BANDON, OREGON, AND ONE-FOURTH TO J. T. SULLIVAN, OF MARSHFIELD, OREGON

WOOD SLICING MACHINE

Application filed November 26, 1928. Serial No. 321,968.

My invention relates to improvements in wood slicing machines, and it consists in the combinations, constructions and arrangements hereinafter described and claimed.

5 An object of my invention is to provide a wood slicing machine which is kept at a uniform temperature while cutting veneer, thus preventing an otherwise inevitable stressing and warping of the parts by reason of partial heating at points in contact with the hot blocks being cut. It is to be understood that the blocks from which the veneer is cut are preheated, and one of the purposes of the present machine is to keep the temperature of 10 these blocks and the cutting elements even during the entire cutting operation.

No originally fixed position of the various parts could be maintained without this feature. The alignments of the knife, the pressure bars, and other parts of the machine are 20 constantly changed in position if the temperature at the center of the device is high and at the more remote parts is lower due to the gradual radiation of heat.

25 A further object of my invention is to provide a device of the type described in which the knife, knife bar, stop bar, pressure bar, and adjusting appliances are mounted upon a single sliding frame that reciprocates on 30 guide bars. The reciprocating frame is connected to the feeding device so as to automatically control the latter.

The device has a micrometer screw control 35 for governing the thickness of the cuts. This control is readily adjustable even while the machine is in operation, and permits a more accurate cutting to within one one-thousandth of an inch. Quick and accurate adjustment is most desirable following up the 40 varying hardnesses inherent in any woods. It is further to be noted that the machine has a maximum of accessibility, enabling the operator to load the feed table, adjust for thickness and pressure, and inspect the entire machine while the latter is in operation.

45 Other objects and advantages will appear as the specification proceeds, and the novel features will be particularly pointed out in the appended claims.

50 My invention is illustrated in the accom-

panying drawings forming a part of this application, in which

Figure 1 is a top plan view of the device;

Figure 2 is a front elevation;

Figure 3 is a section along the line 3—3 of 55 Figure 2;

Figure 4 is an end elevation of a part of the device;

Figure 5 is an end elevation of another part of the device; 60

Figures 6 and 7 are sections along the lines 6—6 and 7—7 of Figure 5.

Figure 8 is a plan view of a part of the device; and

Fig. 9 is a section along the line 9—9 of Figure 8. 65

In carrying out my invention, I provide a main frame 1 that carries a block-supporting bed 2 (see Figure 3). Blocks 3 are placed upon a bed 2 and are urged toward a cutting mechanism by a feeding mechanism.

This mechanism comprises a bar 4 that has a rack 5 secured thereto. A pinion 6 meshes with the rack, and this pinion is actuated by a shaft 7 (see Figure 1). The shaft is 75 manually turned by means of the crank 9 or is turned in one direction by means of a rope 10 that has one end secured to a pulley 11 mounted upon the shaft 7 and its other end connected to a weight 12. Figure 3 clearly shows how the weight 12 tends to rotate the pulley 11 and the shaft 7 for advancing the feed bar 4. 80

The shaft 7 may be locked against rotative movement by means of a manually controlled 85 latch 13 (see Figure 1). This latch engages with teeth on a ratchet 14 that is keyed to the shaft 7. The shaft is carried by bearings that in turn are connected to the main frame 1. 90

The feed bar 4 carries a head 15, and the latter has a block 16 secured thereto that in turn engages with the blocks 3. The feed bar is guided in a bearing 17, and this bearing prevents lateral movement of the bar. 95

I have already stated how the blocks 3 are urged toward a cutting mechanism, and I will now describe this mechanism in detail. Reference to Figure 2 shows the front of the main frame 1 as carrying guide shafts 18 100

and 19. These shafts extend at an angle, and are secured in place by supports 20 and 21. A sliding frame 22 has integral sleeves 23 and 24 that are slidably mounted on the shafts 18 and 19 respectively. The frame 22 is oscillated by a connecting rod 25 and an eccentric 26.

In Figure 1, I show the eccentric as being mounted upon a shaft 27, and the latter is connected to one member of a clutch 28 by means of bevel gears 29. The other member of the clutch is connected to a pulley 30, and the latter is driven by means of a motor 31 through the medium of a belt 32. A hand lever 33 throws the clutch into and out of engagement, and in this way the movement of the frame 22 is controlled.

The sliding frame 22 carries a knife bar 34 and a stop bar 35 (see Figures 2 and 3). The knife bar and stop bar are made hollow and are designed to receive steam, whereby these members are kept at a predetermined temperature. Figure 2 shows steam pipes 36 and 37 as entering the members 34 and 35. The knife bar 34 has an outlet opening 38 for permitting steam to pass therefrom, while the stop bar 35 has an opening 39 for a similar purpose.

The knife bar carries a knife 40 (see Figure 3). This knife is designed to cut a strip of veneer off from the block 3 as the sliding frame 22 is moved downwardly. The knife is positioned with respect to the concave surface 41 of the knife bar 34 so that the strip of veneer will be moved outwardly as the latter is cut. It should be noted that the entire length of the knife contacts with the knife bar, and therefore the former will be kept at the same temperature as the latter, and this temperature will be uniform throughout the entire length of the knife.

The stop bar 35 is adjustable with respect to the knife 40 so that very thin pieces of veneer may be cut from the block. The adjusting mechanism is shown in Figures 4 to 9 inclusive. It will be noted from Figure 4 that the stop bar 35 is triangular-shaped in cross section as shown by the dotted lines, and that this bar has end pieces 42 that are semi-disc shaped. The disc-shaped ends carry gudgeons 43, and the latter in turn are rotatably mounted in openings 44 in shifting plate 45 (note the shape of the plates in Figures 8 and 9). The plates 45 support the stop bar and permit a rocking movement between the bar and the plates so that the front face 46 of the bar may be vertically aligned.

The shifting plates 45 are slidably mounted in brackets 47 as clearly shown in Figure 6. Each bracket 47 is angular in shape and has one face bearing against the end 42 and another face or flange 48 extending at right angles thereto. Figure 7 shows how the flange 48 is clamped to the sliding frame 22 by means of a clamp 49 and a cap screw 50. In this way

the stop bar 35 is supported by the sliding frame 22.

Each angle bracket 47 has a guideway 51 (see Figure 6) for slidably receiving the shifting plate 45, as already stated, the plate carries the stop bar 35, and therefore a movement of the plate in the guideway 51 will move the face 46 further away from the knife 40 so as to vary the thickness of the cut.

I accomplish a micrometer adjustment of the face 46 with respect to the knife 40 by means of the mechanism shown in detail in Figures 5, 6 and 7. It will be noted from Figures 1 and 2 that a crank rod 52 extends throughout the length of the stop bar 35 and is provided with a crank handle 53. The rod is supported in two housings 54 as shown in detail in Figures 5 and 6, and these housings enclose worms 55 carried by the rod 52 and worm gears 56. Figure 7 shows how each worm gear 56 is mounted upon a screw 57 and is locked in place by a nut 58.

The screw 57 is passed through a collar 59 carried by the angle bracket 47. An adjustable thrust collar 60 is mounted upon the screw 57 and bears against the collar 59, whereby the collar 60 and the hub of the worm gear 56 prevent longitudinal movement of the screw 57 with respect to the collar 59.

The screw 57 has a threaded portion that is received in a nut 61 carried by the shifting plate 45 (see Figure 9). A turning of the worm gear 56 will rotate the screw 57 for moving the shifting plate 45 and the stop bar 35 toward or away from the knife 40. The ratio between the number of turns of the rod 52 and the screw 57 is 500 to 1, thus permitting a very fine micrometer adjustment to be effected.

The angle bracket 47 has slots 62 therein (see Figure 5) for receiving cap screws 63 that in turn are threaded into openings 64 (see Figure 4) in the end pieces 42. There is enough play between the cap-screws and the slots 62 to permit angular adjustment of the face 46.

This adjustment is effected by set screws 65 (see Figure 5) that are passed through openings 66 (see Figure 4) in projections 67 carried by the ends 42. The projections 67 straddle a portion 68 (see Figure 9) carried by the shifting plate 45. This construction permits the set screws 65 to be rotated for rocking the ends 42 with respect to the shifting plates 45 and thereby swing the face 46 into vertical position.

The entire stop bar 35 may be raised or lowered, with respect to the sliding frame 22 by means of set screws 69 that bear against the angle brackets 47, and are carried by projections 70 integral with the frame 22 (see Figure 5).

The stop bar 35 carries a pressure bar 71 (see Figure 5), and this bar slightly over-

hangs the face 46 for the purpose of keeping the cut portion of the veneer up against the surface 41 of the knife bar 34, and thus prevent the breaking of the veneer. The pressure bar 71 is adjusted by means of adjusting screws 72 shown in Figure 3, and is locked in adjusted position by means of a pressure bar clamp 73. The clamp in turn is held against movement by lock screws 74, and 10 Figure 4 shows a threaded recess 75 for receiving the screws. Figure 4 further shows a surface 76 for supporting the pressure bar 71.

During the operation of the machine, I 15 provide means for holding the blocks 3 against movement during the cutting operation and for permitting the feeding mechanism to advance the blocks during the return movement of the knife. This means is shown 20 in Figures 2 and 3, and it will be noted from Figure 2 that a clamp bar head 77 has an upright 78 that passes through a guide bracket 79. A spring 80 is disposed on the upright and bears against the bracket 79. This spring 25 holds the clamp 77 down upon the blocks 3. The tension of the spring is adjusted at will by means of a nut 81 that is mounted upon a threaded portion of the upright 78 and bears against the bottom of the spring. It is obvious 30 that any other suitable means of varying the tension of the spring may be utilized without departing from the spirit and scope of my invention.

The clamping head 77 is automatically 35 raised as the sliding frame 22 nears the end of its return stroke. This raising of the head 77 is accomplished by a clamp bar lever 82 (see Figure 2). The lever contacts with the upper edge of the frame 22 as the latter is 40 moved upwardly and is swung by the frame. Figure 2 shows the lever as being connected to the upright 78, and therefore the upright will be lifted and will lift the clamping head 77 free from the blocks 3. The weighted feed 45 bar 4 will now move the blocks up against the face 46 ready for the next cut.

The lever 82 may be manually moved for 50 inserting a new block, and this is accomplished by means of a manually controlled lever 83 shown in Figures 1 and 2, this lever being connected to the lever 82 by means of a chain 84.

From the foregoing description of the various parts of the device, the operation thereof 55 may be readily understood.

The feed bar 4 is retracted and is held in position by means of the latch 13. Blocks 3, previously heated to the desired temperature, are placed upon the bed 2, and then the latch 60 13 is released for permitting the feed bar to engage with the blocks and to move them toward the cutter. The crank 53 is rotated so as to determine the thickness of the veneer to be cut, and then the sliding frame 22 is set into 65 motion. From this point on, the device is

practically automatic, and will cut pieces of veneer from the blocks of the required thickness.

Although I have shown and described one embodiment of my invention, it is to be understood that the same is susceptible of various changes, and I reserve the right to employ such changes as may come within the scope of the invention as claimed.

I claim:

1. A wood slicing machine comprising a support for blocks of wood, means for moving the blocks toward a cutting mechanism, a stop for limiting the movement of the blocks, a cutting knife associated with said stop for cutting pieces of veneer from the blocks, and means for uniformly heating the entire knife and the stop. 75

2. A wood slicing machine comprising a support for blocks of wood, a movable stop, means for feeding the wood against the stop, a knife associated with said stop, means for simultaneously moving said knife and stop, and means for uniformly heating the entire knife and stop. 80

3. In a wood slicing machine, a sliding frame, a knife and a stop carried by said frame, and heating jackets extending throughout the entire lengths of the knife and stop and contacting therewith. 85

4. A wood slicing machine comprising a platform for supporting wood, a cutter carrying frame, a cutter and a stop carried by said frame, means for uniformly heating the entire lengths of said cutter and stop, means for moving the wood toward the frame, and means for reciprocating the frame so that the wood will continuously contact with either the heated cutter or the heated stop. 90

5. A wood slicing machine comprising a support for blocks of wood, a knife movable with respect to the wood for cutting pieces of veneer therefrom, a steam jacket covering one entire side of the knife, and flexible steam conveying conduits leading to the jacket for 100 keeping the entire side of the knife at a uniform temperature. 105

6. In a wood slicing machine, a bed for supporting blocks, a movable frame, a cutter and a stop carried by the frame, a spring-pressed clamp yieldingly engaging with the block being cut, a bell crank lever operatively connected to the clamp and having its other end disposed in the path of the moving frame for freeing the block at the completion of the cutting and the return stroke, and yielding means for advancing the block against the stop when the clamp is disengaged from the block. 115

7. in a machine for slicing a block of wood, a movable frame, a knife carried thereby, a stop carried by the frame, the face of the stop being disposed parallel with the face of the knife, micrometer means for adjusting the stop and including stop carrying supports 120

130

movable at right angles to the working face of the stop, screws for moving the supports, worm gears for rotating said screws, a shaft, worms carried by said shaft and meshing with the worm gears, and a handle for actuating the shaft.

8. A wood slicing machine comprising a platform for supporting work, a cutter, a stop, means for uniformly heating the entire lengths of said cutter and stop, means for moving the work toward the cutter and stop, and means for moving the cutter and stop for causing the work to continuously contact with either the heated cutter or the heated stop.

9. A slicing machine for articles comprising a support for the article, a stop adapted to have the article abutted thereagainst, a cutter for removing slices from the article, and means for uniformly heating the cutter and the stop.

10. A slicing machine for articles comprising a support for the articles, a stop adapted to have articles abutted thereagainst, a cutter associated with the stop for removing slices from the article, means for uniformly heating the cutter and the stop, and means for moving the cutter and stop for causing the articles to continuously contact with either the heated cutter or the heated stop.
